UNITED STATES PATENT OFFICE

SAMUEL E. SPERRY, OF HOLLIS, NEW YORK, ASSIGNOR TO INTERTYPE CORPORATION,
OF BROOKLYN, NEW YORK, A CORPORATION OF NEW YORK

AUTOMATIC EJECTOR SELECTING MECHANISM FOR TYPOGRAPHICAL MACHINES

Application filed October 3, 1931. Serial No. 566,740.

The present invention relates to typographical machines and more especially to line casting machines of the general class shown and described in U. S. Letters Patent No. 436,532, granted September 16, 1890, to O. Mergenthaler, wherein molten metal is forced into a slotted mold against a composed line of character-bearing matrices to produce a printing slug or type bar which is subsequently removed from the mold by an ejector which is advanced against the rear edge of the slug and pushes it edgewise from the mold into a galley.

In the operation of machines of this class, it frequently becomes necessary to vary the length of the mold slot in order to produce slugs of different lengths to accord with the measure of the body or column to be printed. Machines of this class, in practice, are provided with a mold wheel or carrier on which a plurality of molds are mounted so that one or another thereof may be brought into use, and the different molds may have casting slots which differ in length and height so that slugs of several different sizes, according to the requirements of the work in hand, can be cast by merely bringing one or another of the molds into active position. However, the requirements of the various classes of composition will not always enable a sufficient assortment of molds of different sizes to be always present on the mold carrier, so that frequently it becomes necessary to remove one or more of the molds from the mold carrier and replace it or them with another mold or other molds, or one or more of the molds may be partially disassembled and provided with a liner of a different size, such liner being the usual changeable mold member which determines the length of the casting slot therein.

Heretofore, such bringing into operative position of a different mold already mounted in the machine or such changes in the molds or the liners thereof, has required the operator to perform a subsequent operation whereby an ejector blade of the proper width to pass through the slot of the selected or altered mold and to push out the slug cast therein, would be set manually into operative position, and the performance of this ejector

blade selecting or adjusting operation has dependent upon the thoughtfulness or attention of the operator. In consequence, it frequently happens that the operator, through carelessness or inattention, forgets to make the ejector blade setting or adjustment to accord with the selected or altered mold, and upon starting the machine into operation, such has resulted in the presentation of an improper ejector blade to the mold when the latter reaches the ejecting position, and if such blade is too long to enter the mold slot, such ejector blade would jam against the back of the mold liner and, in many cases, cause serious damage.

Attempts have been made to provide safety means to protect the machine from damage due to failure of the operator to bring into use an ejector blade of the proper width to conform with the changed or altered mold, but such safety means as have been proposed have been found deficient or otherwise unsatisfactory for practical use, due to the mechanical intricacies thereof or to their failure to provide a full measure of protection to the machine.

The primary object of the present invention is to provide an improved mechanism which will overcome the above mentioned deficiencies and which will serve effectively not only as a safety means to protect the molds and liners and other parts of the machine from damage but which will also render the selection of the required ejector blade or the proper setting of the ejector mechanism automatic each time a mold having a slot of different length or a mold liner of different length is brought into use.

A more particular object of the invention is to provide an automatic ejector selecting or setting mechanism which is compelled to come into operation each time the operator rotates the mold wheel, which mold wheel rotation always precedes the bringing of a different mold thereon into use or the introduction of a new mold on the mold wheel or changes in the length of the liners of the molds thereon.

A further object of the invention is to provide ejector selecting or setting mechanism

which is so constructed and arranged that failure to operate it in the proper manner will prevent operation of the ejector until the correct operation of the ejector selecting 5 or setting mechanism has been performed.

To these and other ends, the invention consists in certain improvements and combinations and arrangements of parts all as will be hereinafter more fully described, the features of novelty being pointed out particularly in the claims at the end of the specification.

In the accompanying drawings:

Fig. 1 is a side elevation of the mold wheel 15 slide of a line casting machine of the general class referred to, provided with ejector selecting or setting mechanism embodying the present invention;

Fig. 2 is a side elevation of the lower portion 20 of the machine adjacent to and below the mold slide, showing the mold wheel and its turning pinion and also the pinion releasing mechanism which forms part of the present invention;

Fig. 3 is a top plan of the portion of the machine carrying the mold wheel and its turning pinion;

Fig. 4 is a side elevation of the upper portion 30 of the mold slide, showing the ejector selecting mechanism in one of its operative positions;

Fig. 5 is a view similar to Fig. 4, showing the ejector selecting mechanism in another of its operative positions;

Fig. 6 is a view similar to Fig. 4 but showing the ejector selecting mechanism in a different operative position;

Fig. 7 is a transverse vertical section on the line 7—7 of Fig. 6;

Fig. 8 is a perspective view, partly broken away, showing ejector mechanism mounted in the mold slide to be controlled by the improved ejector selecting mechanism;

Fig. 9 is a view similar to Fig. 2 but showing a modified form of pinion releasing mechanism;

Fig. 10 is a detail view in top plan of the operating handle for the ejector selecting mechanism as shown in Fig. 9; and

Fig. 11 is a perspective view of a number 50 of mold liners suitable for use in varying the length of a mold slot and adapted for use with the ejector selecting or setting mechanism provided by the present invention.

Similar parts are designated by the same reference characters in the several figures.

The preferred embodiment of the invention is shown in the present instance and will be hereinafter described in detail, but it is to be understood that the invention is not restricted to the particular construction shown, since equivalent constructions are contemplated and such will be included within the scope of the claims. In the present instance, the 60 invention is shown and will be hereinafter

described, for example, as applied to multiple blade ejector mechanism of the general form shown and described in my prior U. S. Patent No. 1,123,814, granted Jan. 5, 1915, but it is to be understood that the invention is 70 not limited in its application to ejector mechanism of such form but may be modified in different ways to adapt it for application to other forms of multiple blade ejectors such as those now in use. 75

In the present instance, 1 represents the usual mold slide of a line casting machine of the general class hereinbefore referred to, such mold slide being mounted for example in the usual way and having the ejector mechanism mounted therein, the mold slide having as usual a hub 2 projecting laterally therefrom and rotatably supporting the usual mold wheel 6, 3 represents the usual mold gear arm forming part of the main frame of the machine, it being supported toward its forward end by the usual upright post or bracket 4, and 5 represents a cross arm or brace, forming part of the main frame of the machine. The mold wheel 6, in machines of 80 this class, is usually constructed and arranged to carry four molds 6', the mold wheel and the molds thereon being constructed and arranged for example as shown generally in U. S. Letters Patent No. 758,103, granted April 26, 1904, to W. H. Randall. A pinion 7 mounted on a shaft 8 supported in the upright post or bracket 4 meshes with the peripheral gear teeth on the mold wheel and serves to 85 rotate the latter, the rear end of the shaft 8 being driven at appropriate times and to the proper extents by the driving mechanism of the machine to carry the mold on the mold wheel which is in use from normal ejecting position to casting position and from the 90 latter position to normal ejecting position, means being usually provided in machines of 95 this class for holding the mold wheel against turning inadvertently out of proper timed relation with the machine during the intervals between its rotating movements, and the pinion 7 serves as means by which the mold wheel may be rotated independently of its operating shaft 8 in order to bring a different mold on the mold wheel into operative position, it being common in machines of 100 this class to provide a locking pin on the pinion operating shaft 8 and to provide the rear face of the pinion 7 with a recess in which such pin may engage to normally connect the pinion to its operating shaft, the pinion being 105 movable axially on its operating shaft to disengage it from the locking pin and rotatable while so disengaged whereby it may rotate the mold wheel into the desired position. 110

According to the present invention, the pinion 7 is rotatable on its driving shaft 8 but is held from longitudinal movement thereon, and it is operatively connected and disconnected with respect to the shaft 8 by 115 120 125 130

a pin 9 projecting forwardly from a clutch collar 10, the latter being splined on the shaft 8 so that it will always rotate therewith but may move axially thereon to engage and disengage the pin 9 with respect to a recess or hole 11 formed in the rear face of the pinion 7. Normally, the clutch collar 10 will be in forward position with the pin 9 thereon in engagement with the recess or hole 11 in the pinion 7 so that the latter will be driven by the shaft 8 and will be held against rotation independently thereof, but when the clutch collar 10 is shifted rearwardly, the pin 9 thereon will be withdrawn from the recess or hole 11, thereby disconnecting the pinion 7 from the shaft 8 and the pinion will then be free for independent rotation to bring any desired mold on the mold wheel into operative position. The means shown in Figs. 1, 2, 3 and 8 for controlling the driving connection between the pinion 7 and the shaft 8 comprises a clutch shifting arm 12 having a yoke 13 thereon provided with oppositely arranged pins 14 which engage in a circumferential groove 15 in the clutch collar 10, the arm 12 being guided for reciprocation longitudinally of the shaft 8 by a bracket plate 16 secured by screws or other suitable means to the upright post or bracket 4. The arm 12 is pivotally connected to the upper end of a vertical lever 17 which latter is pinned or otherwise fixed at its lower end to one end of a horizontal shaft 18 rotatably mounted in the cross arm 5 of the machine frame, the lever 17 being constantly urged forward by a coil spring 19 which encircles the shaft 18, one end of the spring being fixed to the machine frame and its other end acting on the lever 17. The other end of the shaft 18, as shown in Fig. 3, has a vertical lever 20 pinned or otherwise fixed thereto, and the forward face of this lever is opposite to and in a position to contact with the rear end of an adjustable set screw 21, the latter being carried in a suitable bracket 22 which is pinned or otherwise fixed to a shaft 23, the latter extending longitudinally from the front to the rear of the mold slide along or beneath its lower edge and being guided to slide longitudinally in bearings 39 and 40 formed in a bracket 41 which is fixed by screws or otherwise to the mold slide 1. According to this construction, the spring 19 normally acts to swing the lever 17 and also the arm 12 forwardly, thereby holding the clutch collar 10 in its forward position and the pin 9 thereon in engagement with the recess 11 in the pinion 7 so that the latter will be normally locked to its driving shaft 8, and the pinion 7 cannot be turned independently of the shaft 8 until the clutch collar 10 has been shifted rearwardly into the position shown in Fig. 2, as by rearward movement of the set screw 21 to carry it into engagement with the lever 20 and to swing the latter rearwardly from its

normal position shown in Fig. 3. The means by which the set screw 21 is thus shifted will be hereinafter described.

The ejector mechanism to which the present invention is shown applied is mounted within the mold slide 1 as shown in Fig. 8, and it is of the same general construction as shown and described in my prior patent hereinbefore referred to. For the purposes of the present invention, it is deemed sufficient to describe it as comprising an ejector slide 24 mounted to reciprocate between upper and lower guide rails 25 and 26 formed on the mold slide 1 and extending longitudinally of the mold slide so that the ejector slide may reciprocate forwardly and rearwardly under the action of the connecting link 27 which reaches toward the rear of the machine where it is acted upon at appropriate times by the main driving cams in the well-known manner. A master blade 28 is secured to one side of the ejector slide 24 and extends forwardly therefrom, it having a T-shaped extension 29 projecting forwardly from its forward edge which serves as a key to engage in a correspondingly shaped recess in the rear edge of any one of a set of ejector blades 30 when the master blade 28 is in register or alignment with such ejector blades. The ejector blades 30 are contained within a magazine or blade box 31 which is movable transversely of the path of movement of the master blade 28 to bring any one of the ejector blades into register with such master blade, the magazine or blade box being mounted for this purpose between upper and lower bars 32 which are guided to slide longitudinally in the mold slide 1 and are connected at their rear ends by a yoke or cross bar 33 having a lug 34 projecting laterally therefrom and by which the bars 32 are reciprocated. The sides of the bars 32 toward the upper and lower edges of the blade box 31 are formed with obliquely extending ribs 35, and these ribs engage in corresponding obliquely extending grooves 37 in the upper and lower edges of the blade box. The lug or projection 34 for shifting the bars 32 is arranged to be engaged by an arm 36 which is pinned or otherwise fixed on the shaft 23 so that it will move forwardly or rearwardly therewith. It will be seen that the bars 32 will shift forwardly or rearwardly within the mold slide 1 in accordance with corresponding movements imparted to the shaft 23, and such movements of the bars 32 will transmit motion to the ejector blade box 31 through engagement of the oblique ribs 35 thereon with the oblique grooves 37 in the upper and lower edges of the blade box, causing the latter to shift transversely within the mold slide and to carry the ejector blades therein across the path of the master blade 28. The ejector blades 30 in the blade box are of different widths to conform with slots of different

lengths in the molds that may be used, and the recesses in the rear edges of the ejector blades are all on a common level so that any one of them may receive the key or projection 29 on the master blade, according to the lateral position into which the blade box is shifted. It will be understood that the master blade 28 is withdrawn to its rear position when the blade box is shifted to bring a selected ejector blade therein into use. A guide post 38 having a portion thereon of a shape corresponding within the recesses in the rear edges of the ejector blades so that it may enter such recesses is shown immediately beside the master blade 28, this guide post insuring exact registration of the recess of any selected ejector blade with the key or extension 29 on the master blade. In Fig. 8, the master blade is shown in operative engagement with the smallest or narrowest ejector blade, and the ejector slide 24 is shown in its forwardly advanced position, thus illustrating the manner in which an ejector blade is moved forwardly to extend through the cavity of the mold.

Forward or rearward movement of the shaft 23 to shift the blade box 31 to bring one or another of the ejector blades 30 into register and operative relationship with the master blade 28 is accomplished, as shown in Fig. 8, by an operating lever 42 arranged at the front of the machine, this lever being pivoted intermediately of its length at 43 to an extension 44 of the bearing bracket 41, this operating lever being connected to the forward end of the shaft 23 by a link 45 which is pivotally connected to the shaft 23 and to said operating lever. The operating lever 42 normally occupies the full line position shown in Fig. 3 or the position shown in Fig. 8 but may be swung forwardly into the dotted line position shown in Fig. 3. When the lever 42 is in its normal position, the set screw 21 will be in its forward position beyond the lever 20 and hence the pinion 7 will be locked by the clutch collar 10 to its driving shaft 8, so that the mold wheel 6 cannot be rotated to bring a different mold thereon into operative position unless the clutch collar 10 is shifted rearwardly to withdraw the locking pin 9 thereon from the recess 11 in the mold turning pinion. To accomplish this, the operating lever 42 is swung forwardly about its pivot 43 from the full line position to the dotted line position shown in Fig. 3, such movement of the operating lever causing the shaft 23 to be moved rearwardly so that the screw 21 carried thereby, during the latter part of the forward swing of the operating lever, will contact with the front face of the upper end of the vertical lever 20 and will then swing the lever 20 rearwardly. The rearward swing of the upper end of the lever 20, as will be seen from Fig. 2, will rotate the shaft 18

against the action of the spring 19 and in a direction to swing the lever 17 rearwardly, thereby drawing the arm 12 and the clutch collar 10 rearwardly and thereby withdrawing the pin 9 on the clutch collar from the recess 11 in the pinion 7, and the latter will then be unlocked or free to turn on the shaft 8 and it may be revolved to rotate the mold wheel to bring any desired mold thereon into operative position or to bring a mold thereon from normal ejecting position to the upper horizontal position where it may be replaced by another mold or may be altered to contain a liner of different length. In the construction shown in Figs. 2, 3 and 8, the operating lever 42, when pulled forwardly to its full extent, as shown by the dotted lines in Fig. 2, will lock the shaft 23 against forward or return movement since the link 45 in conjunction with the end of the lever 42 to which it is pivoted forms a toggle the middle pivot of which passes beyond the center line between the pivot 43 and the pivot by which the link 45 is connected to the forward end of the shaft 23, so that the pinion 7 will be thus maintained in unlocked relation with its driving shaft 8 while the mold wheel is being turned, and after the desired mold has been brought into operative position by rotation of the mold wheel, or the operation of mounting a new mold on the mold wheel or of inserting a liner of different length in a mold on the mold wheel, which latter operations also involve rotating the mold wheel to carry the mold to be replaced or altered from the normal ejecting position to casting position and to return such mold to its normal ejecting position, the pinion 7 is again connected to its driving shaft 8 by properly aligning the recess 11 in the pinion with the pin 9 on the clutch collar 10 and then swinging the operating lever 42 back to its normal rearward position, the consequent forward movement of the shaft 23 causing the set screw 21 to recede from the lever 20 so that the latter and also the lever 17 are free to swing forwardly under the action of the spring 19, the forward swing of the lever 17 shifting the clutch collar 10 forwardly and thereby causing the pin 9 thereon to enter the recess 11 in the pinion.

Machines of this class are usually provided with a control or starting handle 46 which, as shown in Fig. 8, is pivoted to the machine frame at 46^a and is connected by a toggle 46^b to bars 146, the rear ends of the latter engaging a clutch lever 47 pivoted on the machine frame and controlling the main driving clutch of the machine so that when the handle 46 is pushed rearwardly the main driving clutch is disengaged and when said handle is pulled forwardly, the bars 146 are drawn forwardly and the main driving clutch is engaged to start the machine into operation. Means is provided by

the present invention for preventing starting of the machine unless the operating lever 42 for setting the ejector mechanism has been returned to its normal position. It will be obvious that should the operator neglect to return the operating handle 42 to normal position so as to effect re-engagement of the pin 9 in the recess 11 of the pinion 7 before starting the machine by pulling the control handle 46 forwardly, the machine would operate in the usual way except that the mold wheel, which is driven by power transmitted to it through the usual pinion shaft 8, would be disconnected. Under such conditions, the mold wheel would not be rotated to bring the selected mold into position in front of the usual metal pot and to align the matrices for casting, but the mold at the top of the mold wheel, which would invariably be of improper size in length or height of its slot or otherwise, would be in position, so that serious damage might occur to parts of the machine, or a metal squirt might result and endanger the operator. To prevent such an occurrence, a depending arm 48 is pinned or otherwise fixed to the forward end of the reciprocating shaft 23, its lower end overlying the forward ends of the rods 146. By this arrangement, when the operating handle 42 is pulled forward to move the shaft 23 rearwardly to disengage the pin 9 from the recess 11 in the pinion 7, the overlying arm 48 will block the rods 146 against any inadvertent forward movement of the machine control handle 46, and hence the main driving clutch of the machine cannot be thrown into engagement to start the machine until the operating handle 42 has been pushed back to normal position.

The present invention provides means for automatically selecting the proper ejector blade 30 to correspond with the length of the slot in the mold which is brought into operative position, and such means will now be described.

The top of the mold slide 1 carries a bracket 49 which is pivoted on said slide by a pin 50 located toward the rear end of the slide. This bracket is provided with upper and lower guide rails 51 and 52 between which a selector finger 53 is slidable in a direction longitudinally of the mold slide. A spring 54 is secured at one end to a pin 55 fixed in the upper rail 51, the other end of this spring being secured to a pin 56 which passes through a longitudinally elongated opening 57 in the upper rail 51 and is secured in the top of the selector finger 53, this spring acting to constantly urge the selector finger 53 forwardly. A projection 58 extends upwardly from the arm 36 into a position to engage a stop pin 59 which is fixed to and projects laterally from the selector finger 53 to control the latter in its forward

movement under the tension of the spring 54. The upper end of the arm 36 has a horizontal and forward extension 60 and the forward end of this extension is provided with a series of steps 61 which extend in a row obliquely to the length of the extension 60 and preferably correspond in number to the number of ejector blades 30 contained in the blade box 31. The selector finger 53 has a pawl 62 suspended pivotally from a pin 63 on said finger, the pawl depending from the selector finger in a position to be engaged by an adjustable stop screw 64 which is secured to a projection on the pivoted bracket 49.

The arm 36 which is connected to the shaft 23 and which moves rearwardly therewith when the operating lever 42 is pulled forward, has an aperture 65 therein through which the lug 34 on the yoke 33 projects. In consequence, rearward movement of the shaft 23 and the arm 36 will shift the lug 34 from a position in engagement with the rear end of the aperture 65, as shown for example in Figs. 5 and 6, to a position in engagement with the forward end of this aperture as shown in Fig. 1, and owing to the connection of the lug 34 through the yoke 33 and slideable bars 32 and the oblique ribs 35 thereon with the blade box 31, the latter will be moved into one of its extreme lateral positions so that one or another of the end ejector blades therein, preferably the widest one within the blade box 31, will be in register with the master blade 28. The arm 36 carries a roller 136 at its upper end, and the bracket 49 is formed with a track or cam surface 137, this roller and cam surface being so arranged that as the arm 36 shifts rearwardly from the position shown in Fig. 5 to that shown in Fig. 1, the roller 136 will engage the cam surface 137 and will act thereon to swing the bracket 49 upwardly from its forwardly and downwardly inclined position shown in Fig. 5 to its upper, approximately horizontal position shown in Fig. 1. It will be understood, from what has been already stated, that the forward movement of the operating lever 42 which shifts the arm 36 into the rear position shown in Fig. 1, disengages the driving pin 9 from the recess 11 in the mold turning pinion 7, so that the mold wheel may then be rotated to bring another mold into operative or active position. After the desired mold has been brought to vertical position in front of the ejector, which may be accomplished by turning the then unlocked pinion 7, the return of the operating lever 42 to normal position, which must take place as previously stated, to permit starting of the machine, moves the shaft 23 and the arm 36 thereon forwardly, and during the initial part of such forward movement of the arm 36, the roller 136 thereon, which moves forwardly with the arm 36, will disengage from the cam track 137 on the pivoted bracket 49.

110

115

120

125

130

135

so that the latter will be no longer supported in its upper or horizontal position but will tilt downwardly about its pivot 50, under the influence of gravity so that it assumes a position such as that shown for example in Fig. 4. Meanwhile or during this forward movement of the arm 36, the upward projection 58 thereon will move forwardly and thus allow the spring 54 to move the selector finger 53 forwardly since the pin 59 on the selector finger is then allowed to advance forwardly, and as soon as the roller 136 on the arm 36 has moved forwardly sufficiently to allow the bracket 49 to tilt downwardly about its pivot 50, the selector finger 53 will have advanced forwardly to an extent sufficient to cause a feeler finger 68 on its forward end to project into a recess 67 in the liner 66 of the mold which occupies ejecting position.

In carrying out the invention, the mold liners of different lengths which, as usual, are changeable to vary the length of the slot or casting cavity in the mold, are provided with recesses of different lengths in their rear edges to cooperate with the feeler finger 68. The left hand liners of molds as commonly used in machines of this class are usually of varying lengths according to the length of the slug which it is desired to cast, while the right hand liner is usually constant in length or, in other words, the right hand end of the mold slot is always located at the same point. In Figs. 1, 4 and 5, the left hand liner 66 which, in each instance, is of the same length, is shown in position in the mold positioned vertically in front of the ejector blade, which is the normal position in which the operator would set the mold before starting the machine, this liner being shown cut away along its rear edge to form a recess 67 having a shoulder 167 at one end, while the liner shown in Fig. 6 is relatively longer and it has a recess 67^a in its rear edge which is relatively shorter than the recess 67 of the shorter liner, said recess 67^a having a shoulder 167^a at one end. Each of the left hand liners to be used with the molds, in carrying out the present invention, contains such a recess, a group of these liners being shown in Fig. 11, the liners being of different lengths and the lengths of the recesses in the rear edges thereof varying, in the present instance, inversely according to the lengths of the liners, and directly according to the lengths of the mold slots produced by such liners and to the widths of the ejector blades which conform therewith.

When the bracket 49 tilts downwardly due to the forward movement of the roller 136 carried by the arm 36, the feeler finger 68 on the forward end of the selector finger 53 swings downwardly in the recess 67 or 67^a in the rear edge of the liner 66 until it stops against the end or shoulder 167 or 167^a of the recess, it being understood that the forward movement of the arm 36 which carries the upper projection 58 thereon forwardly in front of the pin 59 on the selector finger 53 allows the latter to move forwardly to carry the feeler finger 68 into the recess in the rear edge of the liner 66 before the roller 136 disengages from and allows the bracket 49 to swing downwardly about its pivot 50, so that when this downward swing of the bracket 49 takes place, the feeler finger 68 will move downwardly while projecting into the recess in the rear edge of the liner. Fig. 4 represents the relative positions of the parts when the operating lever 42 has been partially returned from its forward position and the shaft 23 has moved forwardly to a point where the roller 136 on the arm 36 has disengaged from and hence no longer supports the bracket 49. During the forward movement of the arm 36 from the position shown in Fig. 1 to that shown in Fig. 4, the selector finger 53 advances to project the feeler finger 68 into the recess in the rear edge of the mold liner 66, as stated, until the pin 56 fixed to the selector finger 53 abuts against the forward end of the slot 57 in the bracket 49, thus arresting the forward movement of the feeler finger 68 under the action of the spring 54, and the downward swing of the feeler finger 68 takes place freely in the recess in the mold liner 66 until it comes to rest on the shoulder 167 at the end of such recess, it being understood that the extent of downward swing or tilt of the bracket 49 and selector finger 53 will vary in accordance with the length or extent of the recess 67 in the mold liner. This downward swing of the bracket 49 and selector finger 53 also brings the lower end of the pawl 62 into a position opposite to or in front of the stepped forward end 61 on the arm 36, the height of the lower end of the pawl 62 relatively to the steps 61 depending on the length of the recess in the rear edge of the liner which controls the extent of downward swing of the bracket 49 and selector finger 53. Further movement of the operating lever 42 back to normal position further advances the arm 36 forwardly, causing the gravity pawl 62, the lower end of which is engaged by an appropriate step on the forward end of the arm 36, to rock about the rear end of the stop screw 64 as a fulcrum, the upper end of the pawl 62 being thereby swung rearwardly and acting through its pivot pin 63, on which the pawl hangs, to shift the selector finger 53 rearwardly against the action of the spring 54. Upon the complete return of the operating lever 42 back to normal position, the selector finger 53, through the action of the pawl 62 rocking on the screw 64, will have been drawn rearwardly to an extent sufficient to withdraw the feeler finger 68 completely from the recess 67 in the mold liner 66, the parts

then occupying the position shown in Fig. 5.

It will be apparent, from Fig. 4, that the forward movement of the arm 36 has not reached the point where it will shift the 5 ejector blade box 31 since the lug 34, through which the ejector blade box is shifted, has not been engaged by the rear wall of the aperture 65 in the arm 36, and in Fig. 5, the lug 34 has been engaged by the rear wall of the 10 aperture 65, and in carrying out the invention, the aperture 65 is so positioned that the lug 34 will be merely engaged by the rear wall of said aperture when the first or lowermost step 61 is in engagement with 15 the pawl 62 and the arm 36 has been moved forward by return of the operating lever 42 sufficiently to withdraw the feeler finger 68 from the recess 67 in the mold liner 66.

The first or lowermost step 61 occupies 20 such a position that when it is engaged by the pawl 62 and the arm 36 has advanced forwardly to the position shown in Fig. 5, the blade box 31, controlled by the lug 34, will occupy one of its extreme lateral positions, for example where the widest ejector 25 blade 30 therein is in register with the master blade 28, and the succeeding steps are so positioned that when they are engaged by the pawl 62 and the arm 36 has advanced forwardly to correspondingly greater extents, the arm 36, then acting on the lug 34, will shift the ejector blade box laterally to appropriate extents to bring correspondingly narrower ejector blades in the blade box into 30 register with the master blade 28. For example, in Fig. 6, the recess 67^a in the mold liner is of a shorter length to correspond with a relatively longer liner which produces a shorter mold slot requiring a correspondingly narrower ejector blade, and this relatively shorter recess in such a liner will allow the bracket 49 to drop to a reduced extent about its pivot 50, so that the gravity pawl 62 depending from the selector finger 53 will 35 have its step engaging end at a higher level and consequently, when the arm 36 is moved forwardly by return of the operating lever 42 to normal position, a step 61 midway back from the lowest step will become engaged 40 with said pawl, and the arm 36 will therefore be allowed to move forwardly to a greater extent before the pin 56 stops against the rear edge of the slot 57 in the bracket 49. The greater extent of forward movement 45 thus allowed the arm 36 causes the lug 34 engaged with the rear wall of the aperture 65 in the arm 36 to be moved forwardly, thus shifting the bars 32 and causing the ejector 50 blade box 31 to be moved transversely of the mold slide to bring an ejector blade 30 of intermediate width therein into register with the master blade 28. The position of the parts shown in Fig. 6 corresponds to that of the same parts shown in Fig. 4 except 55 that the operating handle 42 has been pushed

rearwardly to a slightly further extent so that the arm 36 has been moved forwardly sufficiently to bring the rear wall of the aperture 65 into contact with the lug 34 in Fig. 6, and the ejector blade box 31 will continue to be moved laterally during the further forward movement of the arm 36 until the pin 56 stops against the rear wall of the slot 57. It will be understood that the longest mold liner 66 will have the shortest slot in 75 its rear edge, such longest mold liner requiring the use of the narrowest ejector blade, and that such longest liner when contained in the mold in operative position will arrest the descent of the selector finger 53 80 at a still higher level so that the lower end of the gravity pawl 62 will then be positioned opposite to the uppermost and rearmost step 61 on the arm 36 and hence the latter will advance to the maximum extent before 85 being arrested by the engagement of the pin 56 with the rear end of the slot 57, and in consequence, the lug 34 will be drawn forwardly by the arm 36 to its forward limit, thereby causing the bars 32 having the oblique rails 35 thereon to shift the blade box 31 to its opposite extreme position to bring the narrowest ejector blade 30 therein into register with the master blade 28 for operation thereby, as shown in Fig. 8. From the foregoing, it will be understood that the varying lengths of the recesses in the rear edges of the different length mold liners 66, in conjunction with the diagonal or upwardly and rearwardly extending row of steps 61 on 100 the arm 36 and the cooperative pawl 62 determine the extent to which the arm 36 may advance forwardly and hence, the extent to which the ejector blade box will be shifted laterally and, in consequence, the width of 105 the ejector blade which will be brought into operative relation with the master blade.

Means is provided for positioning and locking the master blade 28 longitudinally during the ejector blade changing operation, 110 in order to insure proper engagement of a selected ejector blade therewith. The construction shown for this purpose comprises a cam block 69 which is pinned or otherwise fixed to the rear end of the shaft 23, and the mold slide 1, as shown in Fig. 1, is provided with a vertically extending recess 70 covered by a plate 71 to form a vertical guide channel for a plunger or bolt 72, the latter having a rearward extension 73 which carries a contact shoe, preferably in the form of a round-nose set screw 74. A stop pin 75 is fixed in the side of the mold slide and projects into a vertically extending recess 76 in the bolt 72 to prevent dropping of the bolt out of its guide channel 70. The bolt 72 extends upwardly beyond the cover plate 71 and a spring 77 is secured to a pin 78 fixed in the upper end of the bolt 72, the other end of the spring being attached to a pin 79 secured

in the cover plate, this spring acting constantly to urge the bolt 72 downwardly. The master blade 28 of the ejector slide 24 is provided with a notch 80 in its lower edge, the forward wall of which is preferably inclined or bevelled as shown in Fig. 8, and the bolt 72 has a correspondingly shaped tongue 81 which is offset laterally from one side thereof so that it underlies the notch 80 and is engageable therewith when the bolt 72 is raised.

When the shaft 23 is in its forward or normal position, the tongue 81 on the bolt 72 will be disengaged from the notch 80 in the master blade 28 since the contact shoe 74 on said bolt will then rest on the lower face 69^a of the cam block 69, and the master blade 28 will then be free to reciprocate without obstruction by the bolt 72. When the shaft

23, however, is pushed to the rear, due to the swinging of the operating lever 42 forwardly in order to release the mold turning pinion 7 and permit the setting up of a different mold on the mold wheel, the bolt 72 will be lifted by the riding of the inclined or raised face 69^b of the cam block 69 against the contact shoe or screw 74 and the tongue 81 on the bolt 72 will then be engaged in the notch 80 in the lower edge of the master blade 28. Such engagement of the tongue on the bolt 72 with the notch 80 in the master blade serves to lock or retain the ejector slide 24 against forward movement whenever the operating lever 42 stands in the forward position, and the bolt 72 also serves as a locating means for the master blade 28, since the position of the notch 80 therein is such that when it registers with the bolt 72, the extension 29 on the master blade 28 will lie in exact transverse alignment with the similarly shaped extension on the guide post 38 and the extension 29 on the master blade will therefore be in exact transverse alignment with the correspondingly shaped recesses in the rear edges of the ejector blades 30 to insure accurate engagement therewith.

Means is preferably provided to insure the complete return of the operating lever 42 to normal position after each operation thereof, such means in the present instance comprising a tension spring 82 which is secured at its forward end to a pin 83 on the bracket 41 attached to the mold slide 1 and fastened at its rear end to a pin 84 which is secured to a plate 85, the latter being secured to the arm 36, the tension of the spring 82 acting to constantly urge the arm 36 and the shaft 23 to which it is fixed, forwardly. This spring will insure the complete return of the operating lever 42 to normal position in the event that the operator should swing the operating lever 42 sufficiently to unlock the toggle formed by it and the link 45 but fail to complete the return movement of the operating lever to normal position.

In the modification shown in Figs. 9 and

10, the operating lever 42 is connected directly to the shaft 23, thus dispensing with the link 45 used in the previously described construction. In this modification, the spring 82 performs the same function of urging the operating lever 42 back to normal position except that, in the absence of the locking link used in the previously described construction, the spring 82 will always tend to return the operating lever 42 to normal position, thus making it necessary for the operator to hold the operating lever 42 forwardly while turning the mold pinion 7 incident to the operation of changing the mold, this arrangement having the advantage that it automatically returns the operating lever 42 to normal position after each mold changing operation.

In the construction shown in Figs. 9 and 10, the pin 9 must be disengaged from the recess 11 in the mold wheel turning pinion 7 before the mold wheel 6 can be revolved to bring another mold into action, as in the previous construction. In order that the pin 9 may be thus disengaged from the pinion 7 but not until the operating lever 42 has been given a full forward stroke, the levers 17 and 20 of the previously described construction are replaced by levers 86 and 87. The lever 86 is pivotally connected at its upper end by a pin 88 to a collar 89 secured to the shaft 23 and the lower end of this lever is pinned or otherwise fixed to one end of the shaft 18. A short crank 90 is pinned or otherwise fixed to the other end of the shaft 18, it extending downwardly therefrom and carrying a crank pin 91 which operates in a slot in the lower end of the lever 87. The lever 87 is mounted to rock on a pivot pin 92 which is fixed in and supported by the arm 4 of the machine frame, and the upper end of the lever 87 is pivotally connected to the clutch arm 12 which, as in the previously described construction, has an upwardly extending yoke which operatively engages the clutch collar 10 which carries the pin 9.

In this modified construction, pulling of the operating lever 42 forwardly causes the shaft 23 to move rearwardly and such rearward movement of the shaft 23 swings the upper end of the lever 86 rearwardly, thereby causing rotation of the shaft 18 and with it the crank 90, both of which are secured to said shaft. Movement of the crank 90 will then produce a forward movement of the lower end of the lever 87 about its pivot pin 92 and the upper end of the lever 87 will therefore move rearwardly, thereby shifting the clutch arm 12 and the clutch collar 10 and pin 9 rearwardly, thus disengaging the pin 9 from the recess 11 in the pinion 7. The arrangement of the levers is such that, while the pin 9, in this instance, is no longer than the pin 9 in the previously described construction, its disengagement from the recess 11 in

the pinion 7 will be considerably slower while the operating lever 42 is being swung forwardly, and preferably and as shown, such disengagement of the pin 9 from the recess 11 in the pinion will not be complete until the operating lever 42 has been moved into its full forward position, whereupon the pinion 7 will be released or unlocked from its operating shaft 8 so that the mold wheel 5 may be rotated, and as soon as the pinion 7 has been turned to bring the recess 11 out 10 of alignment with the pin 9, the operator may release his hold on the operating lever 42 so that the forward end of the pin 9 may 15 ride against the back of the pinion 7, under the action of the spring 82 which tends to move the shaft 23 forwardly, until the recess 11 has again been brought into register with the pin 9, such register of the recess 11 and 20 pin 9 taking place when the next mold on the mold wheel has been brought into operative position. As soon as the recess 11 comes 25 into register with the pin 9, the operating lever 42, under the action of the spring 82, will automatically swing back to normal position and the shaft 23 will correspondingly move forwardly, carrying with it the arm 36, which latter will bring about automatic selection of the proper ejector blade 30 in 30 the same manner as in the construction previously described.

The general operation of automatic ejector selecting mechanism constructed as hereinbefore described is as follows: Assuming that the adjustable liners for the molds are provided in their rear edges with recesses 67 or 67^a of different lengths which vary inversely according to the lengths of these liners and that the ejector blade box of the 35 ejector mechanism contains ejector blades of different widths varying according to the different lengths of the mold slots obtained by the use of the different length adjustable liners, in order to rotate the mold wheel to bring a different mold thereon into operative position or to enable a mold thereon to be replaced by another mold having a different length slot or casting cavity or to enable the adjustable liner of a mold on the mold 40 wheel to be changed for one of a different length and to automatically bring into operation an ejector blade of a proper width to conform with the length of the slot in the mold brought into operative position, it is 45 only necessary for the operator to pull the operating lever 42 to its full forward position and to return or allow this operating lever to return to its normal rear position.

The pulling forward of the operating lever 42 moves the shaft 23 rearwardly, carrying the cam block 69 with it and thereby actuating the bolt 72 to position the master blade 28 for ejector blade shifting operation and locking the master blade in such position 50 and the rearward movement of the shaft 23

also moving the arm 36 rearwardly, the latter portion of the rearward movement of this arm causing it to pick up the lug 34 and to move such lug rearwardly, thereby causing the bars 32 of the ejector mechanism to be drawn 55 rearwardly and causing the ribs 35 on said bars acting on the ejector blade box 31 to shift said box laterally to one of its extreme lateral positions where, for example, the widest ejector blade 30 therein is brought into 60 register or longitudinal alignment and into operative engagement with the master blade 28. The latter portion of such rearward movement of the arm 36 also causes the roller 136 thereon to engage the cam face 137 on the vertically swingable bracket 49, causing the latter, together with the selector finger 53, to swing upwardly into the position shown in Fig. 1, and the final portion of the 65 rearward movement of the arm 36 will cause the upwardly projecting portion 58 thereon to engage the pin 59 on the selector finger 53 and to slide the latter rearwardly against the action of the spring 54 into the position 70 shown in Fig. 1. the feeler finger 68 on the forward end of the selector finger being then retracted from the recess 67 in the rear edge of the adjustable mold liner 66 so that this feeler finger will not obstruct rotation of the 75 mold wheel 6. The forward swing of the operating lever 42 also acts to unlock the mold wheel turning pinion 7 from its driving shaft 8 so that the mold wheel may be turned to effect the mold changing or altering operation, the clutch collar 10 in Figs. 1 to 8, inclusive, being shifted rearwardly to disengage the pin 8 thereon from the recess 11 in the pinion 7 during the latter portion 80 of the forward swing of the operating lever 42, due to the engagement of the set screw 21 moving rearwardly with the shaft 23 with the upper end of the lever 20, and the clutch collar 10 in Figs. 9 and 10 being progressively 85 withdrawn from the recess 11 in the pinion 7 during the forward swing of the operating lever 42 and becoming disengaged from said recess when the operating lever reaches its full forward position, the operating lever 42 being locked in its full forward position by the toggle formed by it and the link 45 in the former instance and being held manually 90 in its full forward position in the latter instance.

While the operating lever 42 thus occupies its full forward position, the arm 48 fixed to the shaft 23 will block the bars 146 from forward movement and hence the machine 95 cannot be started inadvertently into operation by the starting handle 46, and since the mold wheel turning pinion 7 is disconnected from its driving shaft 8, the mold wheel may be rotated to bring another mold thereon into operative position or to bring a mold 100

thereon from the normal vertical or ejecting position to the upper horizontal or casting position for replacement by another mold or for changing of the length of the adjustable liner therein after which the mold wheel may be rotated to return the mold to the normal ejecting position.

After the desired mold change has been made, the operating lever 42 is swung rearwardly or allowed to swing rearwardly under the action of the tension spring 82, the shaft 23 then moving forwardly. The initial part of the forward movement of the shaft 23 causes the arm 36 carried by it to also move forwardly, thereby causing the upward extension 58 on this arm to move forwardly from the pin 59 and also causing the roller 135 to move from a position beneath the cam face 137 on the bracket 49, in consequence of which the selector finger 53 will move forwardly under the tension of the spring 54 and the bracket 49 will swing downwardly by gravity about its pivot 50, thus moving the feeler finger 68 forwardly into the recess 67 in the rear edge of the adjustable liner 66 of the mold which is then in ejecting position, and causing the feeler finger 68 to descend until it comes to rest on the shoulder or inner end 167 of the mold liner, as shown in Fig. 4. During this part of the forward movement of the arm 68, the lug 34 will have a lost motion in the aperture 65 in the arm 36, the forward edge of this aperture advancing from a position in contact with this lug as shown in Fig. 1 to a position removed forwardly therefrom as shown in Fig. 4. The length of the recess 67 in the mold liner 66 determines the extent of downward swing of the selector finger 53 and bracket 49. For example, the liner 66 shown in Fig. 4 is of the shortest length so that the mold slot will be of greatest length, requiring the widest ejector blade, and the recess 67 is of the greatest length, so that the lower end of the gravity pawl 62 depending from the selector finger 53 will descend to a position opposite to the lowest and foremost step 61 on the forward extension 60 of the arm 36. In this case, as the forward movement of the arm 36 continues, the pawl 62, the lower end of which is engaged with the lowermost and foremost step 61, will be rocked about the stop screw 64 as a fulcrum, causing its upper end to swing rearwardly and acting through its pivot 63 to shift the selector finger 53 rearwardly, against the action of the spring 54, until the pin 56 stops against the rear end of the slot 57 in the bracket 49, the feeler finger 68 being then withdrawn rearwardly from the recess 67 in the mold liner 66 as shown in Fig. 5 and the forward advance of the arm 36 being arrested at the moment the rear edge of the aperture 65 in the arm 36 contacts with the lug 34. Since the lug 34 is thus not shifted

forwardly, the ejector blade box 31 will remain at the extreme lateral position which presents the widest ejector blade 30 therein in register with the master blade 28, it becoming attached thereto by the engagement of the extension 29 of the master blade with the correspondingly shaped recess in the rear edge of such ejector blade. During the initial part of the forward movement of the shaft 23 under the tension of the spring 82, and while the arm 36 is moving idly with respect to the lug 34 from the position shown in Fig. 1 to that shown in Fig. 4, the bolt 72 descends out of locking engagement with the master blade 28, the contact screw 74 then riding downwardly to the lower cam face 69^a, and the forward movement of the shaft 23 re-locks the pinion 7 to its driving shaft 8, either during the early portion of the forward movement of said shaft by the retraction of the set screw 21 from the lever 20 in Figs. 1 to 8, inclusive, or by turning of the pinion 7 to bring the recess 11 therein into register with the pin 9 in the construction shown in Figs. 9 and 10. Since an ejector blade of proper width for the mold in operative position has been thus brought into position to be operated by the master blade 28, the machine may be started by pulling forward the usual starting handle 46.

If the adjustable mold liner 66 in the mold brought into operative position is relatively longer than in the example described, forming a relatively shorter slot or casting cavity in the mold and requiring a relatively narrower ejector blade, the operation is the same as above described with the exception that the relatively shorter recess 67^a in the rear edge of such longer mold liner will arrest the downward swing of the bracket 49 and the selector finger 53 at a relatively higher level so that the lower end of the pawl 62 will be opposite to one of the intermediate steps 61 which is offset rearwardly from the lowermost step, and hence the arm 36 will be allowed to advance, during the forward motion of the shaft 23, sufficiently to move the lug 34 forwardly with it, and since the forward movement of this lug, under the action of the bars 32 and the oblique ribs 35 thereon, will act to shift the ejector blade box 31 laterally in a direction to bring a relatively narrow ejector blade 30 therein in register and connection with the master blade 28, a relatively narrower ejector blade to conform with the relatively shorter slot in the mold then brought into use is automatically selected, and the feeler finger 68 is withdrawn from the recess in the rear edge of the mold liner so that the mold wheel may rotate during the operation of the machine without obstruction thereby.

In bringing a mold into use which has an adjustable liner 66 of maximum length forming a slot in the mold of minimum length

and requiring the use of the narrowest ejector blade, it will be understood that the recess in the rear edge of such liner will be of minimum length and it will arrest the downward swing of the selector finger 53 at the highest level so that the lower end of the pawl 62 will be engaged by the uppermost and rearmost step 61 and hence the arm 36 will be permitted to move forwardly to its maximum or full extent, moving the lug 34 forwardly a corresponding distance and thereby shifting the ejector blade box 31 laterally to its extreme position where the narrowest ejector blade 30 registers with the master blade 28, as shown in Fig. 8. By graduating the steps 61 and the recesses 67 in the rear edges of the adjustable mold liners to conform with the varying widths of the ejector blades in the ejector blade box, it will be understood that an ejector blade of the proper width is brought automatically into use to conform with the length of the slot or casting cavity in the mold in operative position.

Since the bringing of another mold already on the mold wheel into operative or active position, or the removal of a mold from the mold wheel and substitution of another mold or the changing of the adjustable liner of a mold on the mold wheel all require rotation of the mold wheel to remove the mold previously in use from its normal vertical position in front of the ejecting mechanism, and such rotation of the mold wheel cannot take place until after the mold wheel turning pinion has been unlocked or unclutched from its operating shaft, which latter operation does not take place until the operating lever has been operated or drawn forwardly to substantially its full extent, and such full operation of the operating lever insures proper and complete operation of the ejector blade selecting mechanism, the selection of an ejector blade of proper width to conform with the length of the slot in the mold brought into use is always insured. The control of the starting handle of the machine by the ejector blade selecting mechanism prevents starting of the machine while the operating lever for the ejector selecting mechanism is pulled forwardly from its normal operative position or if the operator has inadvertently failed to unlock or release it for return to its normal position. Since the ejector selecting mechanism is brought into operation only when the operating lever for such mechanism is actuated incident to a mold changing operation, it will be understood that the ejector selecting mechanism will be idle or inactive during the usual operation of the machine until a change in the mold is made.

The present invention thus provides not only safety means to fully protect the machine or its parts from damage such as would result from the use of an ejector blade of improper width to conform with the length

of the slot or casting cavity in the mold whenever a different mold is brought into use or a change is otherwise made in the length of the mold slot, but it also provides means for automatically selecting and bringing an ejector blade of the proper width into operative position whenever a change is made in the length of the mold slot in which the slugs are to be cast, thereby greatly assisting the operator and saving time in setting the machine to operate with a mold of changed length.

I claim as my invention:

1. In a typographical machine having a mold carrier operative to bring a slotted slug casting mold into active position, means for controlling the mold positioning operation of the mold carrier, and slug ejecting mechanism capable of being set to conform with mold slots of different lengths, means connected to said mold carrier controlling means to operate concurrently therewith and controlled independently of said mold carrier controlling means according to the length of the slot in the mold brought into active position by the mold carrier to set the ejecting mechanism to conform with such mold.

2. In a typographical machine having a mold wheel, a mold wheel turning member and driving clutch therefor, a mold on said wheel having a portion the extent of which has a definite relation to the length of the casting cavity in such mold, and slug ejecting mechanism adjustable to conform with mold slots of different lengths, means connected to the clutch means for said mold wheel turning member to operate concurrently therewith and operative to adjust the ejector mechanism under control of said portion of the mold to conform with the length of the casting cavity of said mold.

3. In a typographical machine having a rotatable mold wheel carrying a slotted slug casting mold, a clutch-controlled turning pinion for the mold wheel, and slug ejecting mechanism adjustable to conform with mold slots of different lengths, means operative to unclutch said mold wheel turning pinion and governed independently of said pinion to adjust said ejecting mechanism to conform with the length of the slot of said mold.

4. In a typographical machine having a rotatable mold wheel carrying a slotted slug casting mold, a clutch-controlled member governing the rotation of the mold wheel to bring the mold thereon into active position, and slug ejecting mechanism adjustable to conform with mold slots of different lengths, means for unclutching the mold wheel governing member, and means operative by the actuation of said unclutching means and governed independently of said member according to the length of the slot of the mold brought into active position by the mold wheel for adjusting the ejecting mechanism to conform with the length of such mold slot.

5. In a typographical machine having a rotatable mold wheel carrying a slotted slug casting mold, a member releasable to permit rotation of the mold wheel to bring the mold thereon into active position, and slug ejecting mechanism adjustable to bring ejector blades of different effective widths into operation, and operating means movable in one direction to release said member and movable in the opposite direction to restore said member, and selecting means for the ejecting mechanism controlled according to the length of the slot of the mold brought into active position by rotation of the mold wheel and set by the movement of the operating means in the direction to release said member and actuated by said opposite movement of the operating means to adjust the ejecting means to bring into operation an ejector blade the effective width of which conforms with the length of the slot of such mold.

6. In a typographical machine having a slotted slug casting mold and slug ejecting mechanism embodying an ejector slide, ejector blades of different widths capable of being set to bring one or another thereof into position for actuation by said slide, and means for locating said slide for adjustment of said blades, common means operative to set said ejector slide locating means in operative position and to set the ejector blades to bring a selected blade into position for actuation by said slide.

7. In a typographical machine having a rotatable mold wheel carrying a slotted slug casting mold, a clutch-controlled turning pinion for the mold wheel, and slug ejecting mechanism embodying an ejector slide, ejector blades of different effective widths capable of being set to bring one or another thereof into position for actuation by said slide, and means for locating said slide during setting of said blades, operating means operative to unclutch said turning pinion to allow rotation of the mold wheel to bring the mold thereon into active position and to set said slide locating means into active position, and selecting means governed according to the length of the slot in said mold and actuated by said operating means to set the ejecting mechanism to bring into operation an ejector blade of a width which conforms with the length of such mold slot.

8. In a typographical machine having a mold wheel carrying a slotted slug casting mold, a clutch-controlled turning pinion for the mold wheel, and slug ejecting mechanism adjustable to conform with mold slots of different lengths, operating means movable from a normal position to unclutch said pinion and allow rotation of the mold wheel to bring the mold thereon into active position, means tending to return said operating means to normal position and re-clutch said pinion, and selecting means set according to the

length of the slot in said mold and actuated by the return of said operating means to normal position for adjusting the slug ejecting mechanism to conform with said mold slot.

9. In a typographical machine having a mold wheel, a clutch-controlled turning pinion therefor, and slug ejecting mechanism adjustable to conform with different length slots of molds on said wheel, operating means movable from a normal position to unclutch said pinion and allow rotation of the mold wheel to bring the mold thereon into active position, means tending to return said operating means to normal position and re-clutch said pinion, a handle embodying means for locking said operating means out of normal position, and selecting means governed according to the length of the slot of the mold brought into active position by the mold wheel and actuated by the return of said operating means to normal position for adjusting the slug ejecting means to conform with such mold.

10. In a typographical machine having a mold wheel, a clutch-controlled turning pinion therefor, slug-ejecting mechanism adjustable to conform with molds on said wheel having slug casting slots of different lengths, and a starting member controlling the operation of the machine, means operative to unclutch said pinion to permit rotation of the mold wheel to bring a mold thereon into active position and to adjust the slug ejecting mechanism to conform with the length of the slot in such mold, and a member set by the operation of said means to prevent actuation of said starting member.

11. In a typographical machine, slug ejecting mechanism comprising ejector blades adjustable to conform with mold slots of different lengths, an adjusting member for the blades, an actuating member for said adjusting member, and selecting means embodying graduated steps and a cooperative pawl capable of being set in different predetermined relative positions and cooperative with said actuating member to govern the blade adjusting movement thereof.

12. In a typographical machine, slug ejecting mechanism comprising ejector blades adjustable to conform with mold slots of different lengths, an adjusting member for the blades, an actuating member for said adjusting member, and selector means including steps graduated according to different blade adjustments of the ejecting mechanism and a controlling member engageable with one or another of said steps and capable of being set in different positions to selectively engage one or another of said steps and thereby correspondingly govern the extent of movement of said actuating member.

13. In a typographical machine, slug ejecting mechanism comprising ejector blades ad-

justable to conform with mold slots of different lengths, an adjusting member for the blades, an actuating member for said adjusting member, and selector means embodying steps graduated according to different blade adjustments of the ejecting mechanism and a pawl mounted to engage one or another of said steps and operative during the blade adjusting movement of the actuating member to govern the extent of such movement.

14. In a typographical machine having a mold wheel and a slug casting mold thereon, slug ejecting mechanism embodying ejector blades adjustable to conform with mold slots of different lengths, an adjusting member for said blades, an actuating member for said adjusting member having steps graduated according to the different blade adjustments of the ejecting mechanism, and a selector member positioned according to the length of the slot of the mold in active position on the mold wheel to cooperate with one or another of said steps to govern accordingly the extent of blade adjusting movement of the actuating member.

15. In a typographical machine, the combination of a mold wheel, a slotted slug casting mold thereon having a portion the extent of which has a definite relation to the length of the slot therein, slug ejecting mechanism embodying ejector blades and adjustable to conform with mold slots of different lengths, an adjusting member for said ejecting mechanism, an actuating member for said adjusting member, a selector member having a feeler finger thereon to cooperate with said portion of the mold, and means interposed between the selector member and the actuating member for governing the extent of movement of the latter, the selector member being movable in one direction to bring the feeler finger into cooperation with said portion of the mold and movable in another direction, under control of said portion of the mold, to position said interposed means.

16. In a typographical machine, the combination of a mold wheel, a slotted slug casting mold thereon having a recess the extent of which has a definite relation to the length of the slot therein, slug ejecting mechanism embodying ejector blades and adjustable to conform with mold slots of different lengths, an adjusting member for said ejecting mechanism, a reciprocatory actuating member for said adjusting member, a selector member having a feeler finger to enter said recess, and selecting means between said actuating and selector members embodying graduated steps on one of said members and a cooperative pawl on the other member, the selector member being movable to an extent according to that allowed the feeler finger by the extent of said recess and in a direction to relatively position said steps and pawl.

17. In a typographical machine, the combination of a mold wheel, a slotted slug casting mold thereon having a recess the length of which has a definite relation to the length of the slot therein, slug ejecting mechanism embodying ejector blades and adjustable to conform with mold slots of different lengths, an adjusting member for said ejector mechanism, a reciprocatory actuating member for said adjusting member having a series of steps thereon spaced obliquely to the direction of movement of the actuating member, a selector member having a feeler finger and carrying a pawl, said selector member being movable in one direction to carry the feeler finger into said recess and movable in another direction to an extent according to that allowed the feeler finger by the length of said recess to position said pawl relatively to said steps, and means cooperative with said pawl during the ejector mechanism adjusting movement of the actuating member to withdraw the feeler finger from said recess.

18. In a typographical machine, the combination of a mold slide having a mold wheel rotatable thereon, a slotted slug casting mold carried by said wheel and provided with a recess the longitudinal extent of which accords with the length of the slot in such mold, slug ejecting mechanism embodying ejector blades and adjustable to conform with mold slots of different lengths, an adjusting member for the ejecting mechanism, a reciprocatory actuating member for said adjusting member, a bracket pivoted on the mold slide to swing vertically at its forward end, a selector member slideable forwardly and rearwardly on said bracket and having a feeler finger at its forward end to enter said recess of the mold on the mold wheel, means controlled by the movement of the actuating member in one direction to advance the selector member to introduce the feeler finger into said mold recess and to swing downwardly therein, selecting means interposed between the actuating member and the selector member controlled by said downward swing of the feeler finger and governing the extent of the movement of the actuating member in said direction, means operative by the movement of the actuating member in said direction to retract the selector member and thereby withdraw the feeler finger from said recess, and means operative by movement of the actuating member in the opposite direction to swing the bracket and selector member upwardly and thereby restore the selecting means.

19. In a typographical machine, the combination of a mold wheel, a slotted slug casting mold thereon adapted to receive liners of different lengths each having a recess therein forming a shoulder the position of which has a definite relation to the length of the respective liner and the length of the mold slot determined thereby, slug ejecting mechanism

- adjustable to conform with mold slots of different lengths, an actuating member for adjusting the ejecting mechanism, a selector member having a feeler finger to operate in the recess of the mold liner and to abut against the shoulder thereof, and means governed by the selector member for controlling the adjustment of the ejecting mechanism by said actuating member.
- 10 20. In a typographical machine, the combination of a rotatable mold wheel, a slotted slug casting mold thereon having a portion the extent of which has a definite relation to the length of the slug casting slot in such 15 mold, a clutch-controlled member governing rotation of the mold wheel to bring the mold thereon into active position, slug ejecting mechanism adjustable to conform with mold slots of different lengths, an adjusting mem-

ber for the ejecting mechanism, a reciprocatory actuating member operative to unclutch and re-clutch said mold wheel governing member by relatively opposite movements thereof and having a lost-motion connection with the adjusting member for the ejecting mechanism to set the ejecting mechanism in a predetermined condition after said mold wheel governing member has been unclutched by movement of said actuating member in one direction, and selecting means governed by said portion of the mold according to the length of the slot therein and cooperative with said actuating member to control the ejecting mechanism adjusting movement thereof in the opposite direction.

In testimony whereof I have hereunto set my hand.

SAMUEL E. SPERRY.
